CLAIM

I claim the ornamental design for a spill tray, as shown and described.

DESCRIPTION

FIG. 1 is a top elevational view of a spill tray showing our new design.

FIG. 2 is a side elevational view thereof, the opposite side elevational view being a mirror image thereof.

FIG. 3 is a front elevational view thereof, the rear elevational view being a mirror image thereof; and,

FIG. 4 is a cross-sectional view thereof taken along the line 4—4 shown in FIG. 1.

The bottom surface of the spill tray forms no part of the claimed design. The broken line disclosure of the U-shaped center cutout is for illustrative purposes only and forms no part of the claimed design.
